CASTER FOR AN INCLINED LEG

Earl J. Winter, 4400 Grove St., Denver, Colo.

Filed Sept. 28, 1959, Ser. No. 57,717

Term of patent 14 years

(Cl. D10—6)

Fig. 3

I claim:
The ornamental design for a caster for an inclined leg, as shown.
